BRAKE FOR COUNTER DIALS

Clayton F. Bane, San Francisco, Calif., assignor,
by mesne assignments, to E. F. Johnson Company, Waseca, Minn.

Application August 10, 1945, Serial No. 610,132

2 Claims. (Cl. 188—72)

1

My invention relates to dials employable, for example, in the adjustment and control of radio apparatus or the like, and more particularly relates to a counter dial and lock arrangement.

Among the objects of my invention are:

(1) To provide a novel and improved counter dial permitting of exceedingly small and accurate adjustment of apparatus to be controlled thereby;

(2) To provide a novel and improved counter dial of simple and rugged design, avoiding the use of worm gears;

(3) To provide a novel and improved counter dial including means for readily interpolating adjustment values between the successive readings of the counter;

(4) To provide a dial having a novel and improved means associated therewith for locking the same in any adjustment position;

(5) To provide a novel and improved dial lock which shall not mar or impair the dial surface;

(6) To provide a novel and improved dial lock which will not have a tendency to upset a predetermined dial position in effecting the locking of such dial;

(7) To provide a dial lock capable of adjustment to fit dials of different thicknesses.

Additional objects of my invention will be pointed out in the following description of a preferred embodiment of the same taken in conjunction with the accompanying drawings wherein:

Figure 1 is a front elevational view of such preferred embodiment of my invention;

Figure 2 is a rear elevational view of the device of Figure 1;

Figure 3 is a side elevational view of the same device;

Figure 4 is a three-dimensional view of the dial lock and its relationship to a dial to be locked thereby;

Figure 5 is a view in section taken in the planes 5—5 of Figure 1.

Referring to the drawings for the details of my preferred embodiment, I provide a backing plate 1, the contour of which is of little significance, though the plate is preferably provided with a plurality of spaced mounting ears 3 offset from the plane of the backing plate to permit of the attachment of the same to the rear of a supporting panel or the like. The backing plate has an opening 5, preferably rectangular in shape, through the upper portion thereof, and at each end of the opening, there is a tab 7 extending rearwardly of the backing plate and preferably formed from the material of the backing plate during the operation of punching the hole therethrough. A counter 9 is carried on a shaft 11 extending between and supported by the rearwardly extending tabs 7, such counter being of the type including a units wheel 13, a tens wheel 15 and a hundreds wheel 17 in alignment with

2

each other and in alignment with a drive pinion 19, suitable spacers 21 and 23 being employed to properly position these elements on the counter shaft. The construction of such counter is conventional and well known.

At a substantial distance below the counter, the backing plate is provided with a bushing 25 in which is journaled a control shaft 27. To the rear of the backing plate, this control shaft carries a pinion 29 preferably of the same size and of the same number of teeth as the counter shaft pinion 19 to which it is geared by an intermediate drive connection.

Such drive connection includes a tab 31 punched out of the backing plate and having a pair of spaced perforated ears 33 bent normal thereto, and a shaft 35 passing through and journaled in these perforated ears. To each end of this shaft there is affixed a pinion 37 and 39 in meshing engagement with that pinion adjacent to it.

By making these drive connection pinions similar, a one to one drive ratio is effected between the control shaft 27 and the counter pinion 19, although it becomes apparent that should any other ratio be desired, this could very readily be realized by changing the dimensions of such of the pinions in accordance with well known design formulas.

30 A calibrated dial 41 mounted on the control shaft in front of the backing plate is frictionally loaded against too free a rotation by the spring washer 43 interposed between the backing plate bushing and the rear surface of the dial.

35 In providing a one to one ratio drive between the control shaft and the counter pinion, the control shaft and, consequently, the dial, will make one complete revolution for each complete revolution of the units wheel and for each one-tenth of a rotation of the tens wheel, etc. Consequently, inasmuch as the dial is capable of calibration to a much higher degree than the units wheel, the units wheel may be disregarded and left blank, while the tens wheel and the hundreds

40 wheel each will be numbered conventionally from zero to nine. Thus the dial can be relied on to accurately interpolate between successive readings of the counter, and by providing the dial with sufficient markings, hair line interpolations 45 may be realized.

45 A piece of sheet plastic 45 is supported from the backing plate on spacers 47 and is of sufficient area to extend over the upper portion of the backing plate including the counter and the upper portion of the dial. This section of sheet plastic is rendered opaque except for that area covering the dial and a small area in front of the foremost digit on the tens and hundreds wheels of the counter to provide a window through which 50 these digits only may be exposed to the observation of an operator.

A reference line 49 may be applied to or scratched on the transparent portion overlying the dial for use in connection with readings on the dial.

When the entire counter dial assembly is mounted on the rear of a panel, the pertinent portion under the plastic sheet may be exposed through an opening in the panel, the plastic sheet serving as protection for the dial.

To preclude accidental or unwarranted tampering with the dial after having once made a desirable adjustment of apparatus, I provide locking means which enables an operator to lock the dial against rotation.

For this purpose, a bracket is added to the backing plate in the form of a laterally extending arm 51, to constitute a support for the locking elements which enter into the make-up of my lock assembly. For all intents and purposes, this bracket may be formed integrally with the backing plate and will be considered as part of the backing plate.

A knob 53 having a stem 55 is positioned with the stem end journaled in an opening 57 in the bracket, the stem having adjacent portions 59 and 61 of different diameters. One of these adjacent portions has a right-hand thread thereon, while the other portion has a left-hand thread. A disc 63 is threadedly mounted on one of the threaded portions of the stem in overlapping relationship to the dial, while a separate disc 65 is threadedly mounted on the other threaded portion of the stem in underlapping relationship to the dial, each of the discs having notches 67 in the edge thereof capable of alignment with the notches in the other disc.

A retaining pin 69 anchored to the backing plate bracket 51, preferably by threading the same therein, and extending through aligned notches, will serve to preclude rotation of either or both of said discs, at the same time, without impairing the ability of such discs to move linearly in response to rotation of the knob 53.

Such rotation of the knob, due to the reverse threads on its stem, will cause simultaneous linear movement of the discs in opposite directions, that is either toward each other or away from each other. In one such direction of movement, the discs will simultaneously approach the dial and clamp the same against rotation, and by such function, lock the entire counter dial assembly. In the opposite direction of movement, of course, the assembly will be unlocked.

By withdrawing of the pin 69, either disc may be manually rotated to adjust its position on the stem. This permits of symmetrical positioning of the discs with respect to the dial, as well as providing adjustment for dials of different thicknesses. With dials of average thickness, locking and unlocking of the same may be accomplished through less than one complete turn of the knob.

A washer 71 positioned on the pin between the two discs, serves to maintain substantial parallelism of the discs when the discs are in clamping engagement with the dial.

In operation, the discs approach the dial without rotation, and consequently cannot drag or scrape on the dial during locking or unlocking, nor can they upset any adjustment of the dial which it is desired to maintain through the use of the lock. It furthermore becomes impossible to distort or bend the dial during locking. Thus the lock is capable of performing a highly desirable function without any deleterious results to the dial mechanism.

While I have described my invention in its preferred form and in considerable detail, the same is subject to modification and alteration, without departing from the underlying principles involved, and I accordingly do not desire to be limited in my protection to the details thus disclosed, except as may be necessitated by the appended claims.

I claim:

1. A dial lock assembly comprising a knob having a stem adapted to engage a supporting plate, said stem having adjacent portions, one of said portions having a right-hand thread thereon, while the other portion has a left-hand thread; a disc threadedly mounted on one of said threaded portions of said stem; a separate disc threadedly mounted on the other threaded portion of said stem; each of said discs having a plurality of disc openings therein alignable within a fractional turn of either disc; and means precluding rotation of either of said discs without impairing simultaneous linear movement thereof in opposite directions in response to rotation of said knob, said means including a pin adapted to pass through a pair of said alignable disc openings.

2. A dial lock assembly comprising a supporting plate; a knob having a stem pivotally engaging said supporting plate, said stem having adjacent portions of different diameters, one of said portions having a right-hand thread thereon, while the other portion has a left-hand thread; a disc threadedly mounted on one of said threaded portions of said stem; a separate disc threadedly mounted on the other threaded portion of said stem; each of said discs having a notch in the edge thereof capable of alignment with the notch in the other disc; a pin anchored to said supporting plate and extending through said notches to preclude rotation of either of said discs without impairing simultaneous linear movement thereof on said stem in opposite directions in response to rotation of said knob; and a spacer on said pin between said discs, said spacer having a thickness approximating that of a dial with which said lock is used.
